KNITTING MACHINE

Albert E. Stewart, Franklin, N. H., assignor to
 Acme Knitting Machine & Needle Company,
 Franklin, N. H., a corporation of New Hampshire

Application February 2, 1932, Serial No. 590,411

2 Claims. (Cl. 66—134)

This invention relates to knitting machines of the circular or rotary type and is more especially concerned with mechanisms for controlling the feeding of thread to the needles of such machines.

5 In most knitting machines the changing of the threads or the introduction of a reinforcing thread is effected by means of thread guiding fingers cooperating with suitable cutting and clamping apparatus, all located within the circle of the needles. In some machines, however, the space within the circle of needles is occupied by mechanism which makes it impossible to use the ordinary thread fingers and thread clamps. In 10 such machines, therefore, it becomes necessary to perform the thread changing and splicing operations in a different manner. This has been done heretofore by twisting a new thread to be introduced on to the thread which is being knit into the goods to cause the latter to carry in the additional thread. While such an arrangement can 15 be used satisfactorily for some purposes, it obviously is not suitable for use in such operations as making a high splice in a stocking or in reinforcing the bottom of the foot portion of the stocking to make what is commonly known as a double sole.

The present invention deals especially with these considerations. It aims to devise a mechanism for introducing a reinforcing thread, or 20 making some other change in the threads with which the knitting operation is being performed, while leaving the space within the circle of needles substantially free and at the same time controlling the handling of the threads accurately and entirely automatically. The invention will 25 be herein disclosed as embodied in a mechanism adapted especially for use in making the splice or reinforcement just above the heel of a stocking, or in reinforcing the lower portion of the foot, but it will be evident that features of the invention 30 are also applicable to thread changing and other thread handling operations in a circular knitting machine.

The nature of the invention will be readily 35 understood from the following description when read in connection with the accompanying drawings, and the novel features will be particularly pointed out in the appended claims.

In the drawings, 40 Figure 1 is a perspective view of portions of a knitting machine equipped with mechanism embodying this invention;

Fig. 2 is a plan view of the construction shown in Fig. 1;

Fig. 3 is a vertical, sectional view, partly in ele-

vation, showing parts of the mechanism illustrated in Figs. 1 and 2;

Fig. 4 is a plan view, partly in horizontal section, showing certain of the parts which control the movement of the supplemental or splicing thread into and out of position to be taken by the needles;

Fig. 5 is a perspective view of the thread ring and certain of the parts associated therewith, no attempt being made in any of these figures to 10 show the correct spacing of the needles.

Fig. 5a is a diagrammatic view illustrating the path taken by the splicing thread under certain conditions;

Fig. 6 is a view, partly in side elevation and 15 partly in vertical section, of the thread clamping and cutting mechanism;

Fig. 7 is a perspective view of said thread clamping and cutting mechanism;

Fig. 8 is a horizontal, sectional view showing 20 the manner in which the splicing thread is cut and clamped;

Fig. 8a is a fragmentary view from a point inside the needle cylinder illustrating the relative positions of the thread guide, the thread clamp, 25 and the needles as they descend to the knitting point;

Fig. 9 is a plan view of parts of the operating mechanism for the thread cutter and clamp;

Fig. 10 is a perspective view of a stocking illustrating some of the work which may be done with the mechanism provided by this invention;

Fig. 11 is a vertical, sectional view, partly in elevation, illustrating a thread tensioning device which may be used in the machine, together with 35 mechanism for operating it intermittently;

Fig. 12 is a plan view of certain parts shown in Fig. 11; and

Fig. 13 is an end view of parts of the operating mechanism shown in Fig. 11. 40

For purposes of illustration the invention is herein shown as embodied in a hosiery knitting machine of the type shown in my pending application Serial No. 405,949, filed November 9, 1929, now Patent No. 1,943,265, the invention disclosed 45 in said application being illustrated as applied to the circular or rotary hosiery knitting machine known commercially as the "Acme Model D machine". For a more complete disclosure of the latter machine reference may be made to Canadian Patent No. 200,057, dated May 11, 1920. While the invention is equally applicable to machines of the stationary and revolving needle cylinder types, the particular machine shown is of 50 the latter construction and includes an upright 55

needle cylinder 1 carrying a vertical series of latch needles 2, together with the usual cams and other operating instrumentalities for actuating said needles to cause them to knit a stocking automatically in the usual manner.

The machine shown in my pending application above identified is equipped with a looper head 4, Fig. 1, carrying loopers 5 which may be utilized to wrap additional threads around any selected 10 needle or needles 2 for the purpose of producing design or pattern effects, such wrapping operations taking place while the needles continue to knit uninterruptedly with one or more main threads. In the present machine a main thread 15 T, Figs. 1 and 5, is fed through the thread ring or latch ring 6 to the needles 2, either alone or together with a plating thread P. An additional reinforcing or splicing thread may be twisted on to one of these main threads for the purpose of 20 reinforcing the heel and toe of the stocking being knit by known means, but when it is desired to splice the portion of the stocking S, Fig. 10, immediately above the heel, as indicated at h, or the sole of the foot, as shown at f, a different 25 arrangement must be used because of the necessity for starting and stopping the splicing operation on substantially the same needles in each course of knitting so that the edges of the spliced sections will be substantially straight. Furthermore, 30 because of the fact that most of the space inside the thread ring is occupied by the looper head and the parts carried thereby, the mechanism for handling the reinforcing or splicing thread must be located outside the circle of needles. The machine shown is equipped with 35 mechanism for satisfying these conditions.

Referring more especially to Figs. 2 to 5, it will be seen that the latch ring 6 is cut away at the point 7, Fig. 5, to admit one end of a cutting and 40 clamping device which is designated in general by the numeral 8. As best shown in Fig. 5 the forward or inner end of this device is located in the notch formed by the wave of needles 2 where they 45 descend to the knitting point, so that the clamping and cutting operations can be performed closely adjacent to the knitting point. This device cooperates with a thread guide 10 to support a reinforcing or splicing thread R in position to be taken by the needles.

The thread guide 10 consists simply of a tube 50 which is supported in a slide 12, best shown in Fig. 4, this slide being slotted, as indicated at 13, to receive a guiding lug 14 which is formed integral with, or is secured rigidly to, the latch ring 6. It will be seen that when the thread guide 10 is in 55 the position shown the thread R will be held stretched between the forward or inner end of the tube and the thread clamp and will occupy a line approximately tangential to the circular series of needles but intersecting the path of movement of the hooks of the needles as they descend to the knitting point. In other words, the thread at this time is in position to be taken by the needles and knit into the fabric. If, however, the slide 12 is 60 moved toward the clamp 8 the thread R then will be swung outwardly away from the circle of needles into such a position that the hooks of the needles cannot take it, and knitting with this thread thereupon will be interrupted.

70 Normally the thread guide 10 is held in its operative position, as shown in Fig. 4, by means of an upright pin 15, Figs. 2, 3 and 4, which is secured rigidly in a swinging arm 16, this arm being pivoted at 17 to a sliding plate 18. A coiled spring 75 20 is connected with the arm 16 and operates

through the pin to hold the slide 12 yieldingly in the position shown, this movement of the slide under the influence of the spring being limited by a set screw 21, Fig. 2. The movement of the arm 16 relatively to the plate 18 is limited by the pin 5 22, Fig. 4.

In knitting either of the spliced sections h or f, Fig. 10, the thread R must be presented to the needles during approximately half of each revolution of the needle cylinder, and must then be 10 withdrawn from its feeding position so that the needles cannot take it during the other half of the revolution of said cylinder. In other words, this thread must be fed to approximately half of the needles in the circle but not to the other half. In 15 order to control the thread in this manner a cam 23, Fig. 2, is mounted on the sinker ring to revolve with the needle cylinder and has an angular extent of slightly less than 180°. The forward end 24 of this cam is made square and is arranged 20 to strike a shoulder 25, Fig. 4, on the end of the swinging arm 16. When this occurs said arm will be swung far enough to carry the pin 15 away from the slide 12, whereupon a spring 26 operates through the arm 27 and the engagement of said 25 arm with a shoulder 28 on the slide to move this arm toward the cutting and clamping device 8, thus carrying the thread R out of operative relationship to the needles 2, as above described. The slide 12 remains in this position until the trailing 30 end of the cam 23 moves out of engagement with the end of the arm 16 at which time the spring 26 again returns the slide 12 to its original position, as shown in Fig. 4, the spring 26 overcoming the action of the spring 26. This returns the thread 35 guide 10 to its operative position where the reinforcing thread R is again taken by the needles and knit into the fabric.

Immediately after the needles begin to take the thread the clamping and cutting device 8 40 should be opened to release the thread, and approximately at the time that the thread guide 10 is again moved into its inoperative position the thread clamp should be opened to receive the thread and should be operated to cut the thread 45 between the needles and the clamping point.

Referring more especially to Figs. 6 to 9 it will be seen that the clamping and cutting device comprises a supporting piece 8 which is mounted rigidly on the arm 28, Fig. 2, and has a tapered 50 nose which projects through the aperture 7. Positioned in a slot formed in this supporting member 8 is a stationary clamping piece 30 which is provided at its extremity with a downwardly extending finger 31. This clamping piece lies between two blades 32 and 33, respectively, which are arranged to reciprocate in slots provided in the part 8 at opposite sides of the member 30. The blades are removably secured to a plunger 34 which is mounted to reciprocate in a guiding 55 slot 35, Fig. 7, formed in a cap piece 36 which is screwed to the support 8. Secured rigidly in and extending downwardly from the slide or plunger 34 is a pin 37 which is grooved, as shown at 38, to receive a latch piece 40 that is connected by 60 a coiled spring 41 to a lug 42 projecting upwardly from one member of a stationary guide 43. This guide is supported on a bracket member 72, Fig. 3, and it supports a plunger 44 for sliding movement forward and backward in a direction parallel to the slide 34. When this plunger is moved 65 backwardly its rearward end strikes the pin 37, thus operating through the slide 34 to move the blades 32 and 33 backwardly so that their extreme forward ends lie behind or to the left, Fig. 6, of the 75

clamping finger 31. This opens the thread clamp. Operation of the clamp in this manner is effected, for the purpose of releasing the thread, by means of the cam 45, Fig. 2, which rotates with the needle cylinder and with the cam 23 but is located at a slightly higher elevation than the latter cam. The angular extent of the cam 45 determines the length of time that the thread clamp will be held open. The clamp is allowed to close immediately after it has released the thread, and it is again opened by another cam 46, Fig. 2, immediately after the thread guide 10 has been moved out of its operative position. Both cams 45 and 46 are mounted on the sinker ring. As soon as the cam 46 passes out of engagement with the plunger 42 the spring 41 forces the blades 32 and 33 forward again to close the clamp and to cut the thread, the extent of this closing movement being limited by the adjustable screw 39. Referring to Fig. 8 it will be seen that the blade 32 which is nearer to the thread guide 10 has a rounded forward edge to grip the thread R between the blade and the clamping finger. The other blade 33 has a sharpened edge and cooperates with one face of the finger 31 to cut the thread, the finger acting as a shearing block. Due to the fact that the thread is cut closely adjacent to the knitting point, the length of loose thread left inside the fabric can be made very short, as shown, for example, at r, Fig. 5.

The engagement of the thread with the clamp prior to the cutting operation is facilitated by the fact that the thread is no longer being taken by the needles but is stretched between the last needle which has taken it and the inner end of the thread guide 10. This thread guide has moved from its operative position, as indicated at 10 in Fig. 5a, into its inoperative position 10'. As the last needle holding the thread moves away from the knitting point it lifts the thread R directly into the cut-away space behind the clamping finger 31, this action also being facilitated by the fact that the needles are moving away from the clamp. Due to this arrangement a positive and certain engagement of the thread with the clamping and cutting device is effected. This action is also assisted by the movement of the thread guide toward the clamp and the fact that it is positioned at a higher elevation than the clamp.

As above stated, it is important that the reinforcing operation in successive courses of knitting shall begin and end with the same needles. In other words, that a certain needle shall always take the reinforcing thread initially in each course, and that another needle at a later point in the cylinder shall knit in the final stitch with this reinforcing thread in each course. I have found that this object can be conveniently accomplished by so positioning the guide 10 and the clamp 8 that the guiding and clamping points between which the thread is initially stretched for engagement with the needles shall cause this thread to intersect the path of travel of the needles at a point where they are descending toward the knitting point. On this downward slope of the wave of needles the needle hooks are separated by a substantial distance from each other so that by making the thread cut this path of travel of the hooks on the downward slant, the same hook can be made to initially engage the thread in practically every revolution of the needle cylinder while the reinforced section of the fabric is being made. Accuracy in timing necessary to obtain this degree of control also is facilitated by locating the controlling cam 23 for the

thread guide closely adjacent to and partly surrounding the needle cylinder where it rotates in unison with said cylinder.

During the knitting of the heel and toe it is desirable to move both the thread guide and the cutting and clamping device out of their normal positions so as to avoid any possibility of interfering with the knitting operations while the cylinder is reciprocating. For the purpose of moving the thread guide and the operating mechanism associated therewith, the swinging arm 16 is supported on the slide 18, as above described, and this slide is mounted in a bracket 49 to move backward and forward in an approximately radial direction with reference to the needle cylinder. Projecting laterally from the slide 18 is a pin 48 which is arranged to be engaged by one arm of a bell crank lever 50 fulcrumed on the bracket 49 at 51, Fig. 3. A cam 52 secured rigidly on the pattern drum shaft 53 is provided with cam lugs 54 and 55 arranged to engage a pin 56 projecting laterally from the lever 50. When such engagement occurs the lever is swung in a clockwise direction, Fig. 3, thus operating through the pin 48 and slide 18 to move all of the parts carried by said slide into their forward or operative positions. As soon, however, as one of the cam lugs 54 or 55 moves out of engagement with the pin 56, the slide 18 and the parts mounted thereon are immediately moved rearwardly out of their operative positions by means of a coiled spring 57 located in the bracket 49 and bearing against a plunger 58 which, in turn, engages a depending arm 60 secured rigidly to the rearward end of the slide 18.

The movement of the slide 18 out of its operative position carries the pin 15 toward the left, Fig. 4, out of engagement with the shoulder 61 of the slide 12 on which it normally bears, and permits the spring actuated arm 27 to move the slide toward the clamp 8 and thus to carry the thread guide 10 into its inoperative or non-feeding position. Upon the return movement of the slide 18 the pin 15 engages the inclined face 62 of the slide 12 and moves this slide back into its former position again.

The pattern drum shaft 53 is a part of the Model D Acme machine, previously referred to, and is under the direct control of the main pattern chain of the machine, the arrangement being such that the shaft 53 makes one complete revolution during the knitting of each stocking. In the particular arrangement shown the cam lugs 54 and 55 on the cam 52 are provided to hold the slide 18 in its forward or operative position during those periods only in which the reinforced sections h and f are being knit.

A mechanism similar to that above described is provided to move the thread clamping and cutting device into and out of its operative position, this mechanism comprising a cam 64, Figs. 1 and 2, secured fast on the pattern drum shaft 53, the lugs on said cam being arranged to engage a roll or stud 65 which is carried by and projects laterally from a lever 66 fulcrumed on the machine frame at 67, Fig. 1. A link 68 connects the upper end of this lever with one arm 70 of a bell crank lever fulcrumed on the pin 71 which is supported in the stationary bracket 72 carried by the post 73. The other arm of said bell crank lever consists of the support 28 on which the cutting and clamping device is mounted. A coiled spring 74 acts through the links 68 to hold the cutting and clamping device normally in its operative position.

Some tension should be applied to the reinforcing thread R, and for this purpose it may be run through a thread tensioning device 75, Figs. 1 and 2, of a common type. Due to the fact, however, that this reinforcing thread is fed to the needles in a plating relationship to the main thread or threads, and to the further fact that when two threads are fed in this manner the tensioned thread tends to come to the outside of the fabric, it is usually preferable to have the reinforcing thread R run as freely as possible. At the same time considerable tension should be applied to it at approximately the time that it is being moved out of the position to be taken by the needles in order to avoid the presence of any substantial amount of slack thread adjacent to the needles. For this reason I prefer to equip the machine with a device for applying an intermittent tension to the thread R. This device is illustrated in Figs. 11, 12 and 13. It may conveniently be mounted on the link 68, previously referred to, and consists of a small bracket 77 secured rigidly to said link and carrying an upright hollow post 78 at its outer end. A thread disk 80 is secured horizontally on the upper end of said post. Extending through the post 78 is a plunger or pin 81 which serves to center a loose thread engaging disk 82 adapted to rest on the lower disk 80 and pressed lightly against the latter disk by a spring 83 backed up by a collar 84 which is fastened to the upper end of the pin 81. A coiled spring 85 acts on said pin to pull it downwardly. When the parts are in this position the thread R running between the disks 80 and 82 is subjected to considerable drag applied to it by the weight of the disk 82 and the pressure of the spring 83, the degree of friction so applied being predetermined by the adjustment of the collar 84 on the pin 81. When, however, the pin 81 is lifted it also raises the upper disk 82 due to the fact that the latter disk rests on a shoulder on the pin, and the drag or tension on the thread then is removed.

It is desirable to have this drag or tension applied at substantially the instant that the thread guide 10 moves out of its operative position and to have the tension relieved when the thread guide begins to move back to its operative position again. This action occurs in every revolution of the needle cylinder. Consequently, an operating mechanism is provided to move the pin 81 up and down comprising a cam 86, Fig. 11, secured fast on the main shaft 87 of the machine. An upright pin 88 rests on the periphery of said cam and is arranged to engage one arm of a bell crank lever 90, the opposite arm of which is positioned to bear against the end of a slide 91. The shaft 87 is the main shaft of the machine and is geared directly to the needle cylinder so that it makes one complete revolution during each revolution of the needle cylinder. When the high part of the cam 86 lifts the pin 88 this movement is transmitted through the connections just described to the slide 91 causing the left-hand bevelled end, Fig. 11, of the slide to raise the pin 81 and thus to lift the upper thread tensioning disk 82. As the pin 88 drops off the high part of the cam the spring 92 withdraws the slide 91 and allows the pin 81 to drop again. The extent and timing of the high part of the cam 86 is such that the reinforcing thread R is gripped and released at the desired points in each revolution of the needle cylinder.

When the reinforcing thread is not being knit into the goods the link 68 is moved forward by its

connections with the cam 64, as above described, and such forward movement carries the bracket 77 and the thread tensioning device supported thereby out of the range of operation of the bell crank lever 90, but these parts subsequently are restored to their cooperative relationship when the link 68 is again moved backwardly to swing the thread clamping and cutting device into its operative position. This backward movement of the thread tensioning device may be timed to occur substantially simultaneously with the movement of the slide 12 into its operative position so that both movements will cooperate to tighten the thread between the clamp 8 and the guide 10.

It may here be pointed out that when the slide 18 is in its rearward or inoperative position with the pin 56 out of engagement with either lug 54 or 55, the thread clamping and cutting device is held in its rearward or inoperative position by the engagement of one of the lugs of the cam 64 with the pin 65. The clamp, however, is still holding the end of the reinforcing yarn. When the splicing or reinforcing yarn is to be initially introduced to the needles at the beginning of sections f or h of the stocking S, Fig. 10, the rotation of the shaft 53 moves the slide 18 forward through the mechanism above described, thus carrying the slide into its operative position. At the same time the pin 65, Figs. 1 and 2, is released by the lugs of the cam 64 and allows the spring 74 to swing the arm 28 forward, thus carrying the cutting and clamping device into its operative position. At substantially the completion of this movement, together with a similar movement of the slide 18, the reinforcing yarn is brought into a position tangentially intersecting the circle of needles so that it will be taken by the needles.

The invention thus provides a mechanism for introducing a thread to the hooks of the knitting machine needles and withdrawing it therefrom at times which may not only be predetermined accurately in the cycle of operations of the machine, but also at definitely controlled points in the revolution of the needle cylinder. This mechanism has been found in practice to afford an exceptionally accurate control of the feeding of the thread and to be extremely reliable in operation. Since all of the parts for handling the reinforcing thread and the means for operating them are located outside of the circle of needles, the entire space within said circle is left free. In addition, the accurate control of the thread and its delivery to and removal from the needles at specified points in the circle of needles is of great practical importance in making straight lines at the opposite edges of the reinforced sections. With this mechanism, also, exceptionally short free ends of thread are left at the opposite ends of each course of reinforced knitting so that no additional trimming is necessary.

While I have herein shown and described a preferred embodiment of my invention, it will be evident that the invention may be embodied in other forms without departing from the spirit or scope thereof.

Having thus described my invention, what I desire to claim as new is:

1. In a circular knitting machine, the combination with knitting instrumentalities including a circular series of needles, an upright rotary cylinder supporting them, and cams for operating said needles, of a normally stationary thread clamping and cutting device mounted outside the circle of said needles and extending under the

latch ring but positioned to grip a thread at a point closely adjacent to the bottom of the needle wave where the needles cast their stitches at the knitting point, a thread guide positioned entirely outside of said circular series of needles and above the latch ring and having a thread guiding eye located at a substantially higher elevation than said cutting and clamping device and cooperating with it to support a thread in a line extending from said clamping device upwardly and backwardly with reference to the direction of rotation of the needles in such a position that it will be taken by said needles as they descend in approaching the knitting point, means governed by the pattern mechanism of the machine for moving said thread guide and said clamping and cutting device away from the needle cylinder preparatory to reciprocating said cylinder and toward said cylinder at the conclusion of reciprocating knitting, and cams revolving in fixed relationship to the rotation of the needle cylinder for operating said clamping and cutting device and moving said thread guide toward and from said device at predetermined points in each revolution of the needle cylinder to cause said thread to be taken by the same group of needles in each revolution of the machine, said group of needles forming a fraction only of the entire circle of needles.

2. That improvement in methods of feeding a reinforcing thread to a circular series of needles in a rotary knitting machine, which consists in

clamping the thread at a fixed point closely adjacent to the bottom of the needle wave where the needles cast their stitches at the knitting point, guiding the thread at a point outside the circle of needles but spaced from said clamping point in a direction opposite to the direction of rotation of the needles and so located with reference to said clamping point as to hold the thread in a straight inclined line running from said clamping point to said guiding point but intersecting the path of the hooks of the needles as they descend to the knitting position, moving said thread guiding point toward said clamping point but along a path extending in approximately the same general direction as that in which the needles adjacent to said path are moving forward and at a substantially higher elevation than said clamping point to prevent the needles from taking the thread when desired, moving said guiding point in the opposite direction to present the thread to the said needles again, maintaining said thread clamping point stationary and said thread guiding point entirely outside of said circle of needles during said movements, applying a strong tension to said thread during the first mentioned movement of said guiding point, relieving said tension during the opposite movement of said guiding point and cutting said thread in front of the clamping point substantially simultaneously with each thread clamping operation.

ALBERT E. STEWART. 30
